UNITED STATES PATENT OFFICE.

FRANK T. PARRITT, OF BLOOMINGTON, ILLINOIS.

DESIGN FOR A CASING FOR COIN-ACTUATED MACHINES.

SPECIFICATION forming part of Design No. 27,482, dated August 3, 1897.

Application filed April 12, 1897. Serial No. 631,857. Term of patent 31 years.

To all whom it may concern:

Be it known that I, FRANK T. PARRITT, a citizen of the United States, residing at Bloomington, in the county of McLean and State of Illinois, have invented and produced a new and original Design for the Casing of a Coin-Actuated Machine, of which the following is a specification, reference being had to the accompanying drawing, in which the figure represents an elevation of a casing constructed in accordance with my invention.

The leading feature of my design consists in the peculiar configuration given to the casing and the ornamental legs by which it is supported.

In the said drawing the reference-numeral

1 designates the casing, having the appearance and configuration of a cigar, with the pointed end down. This casing is supported by ornamental legs 2, secured thereto at the 20 pointed end, which legs consist of the angular feet 3, the inclined leg portions 4, and the upper triangular portions 5.

Having thus described my invention, what I claim is—

The design for a casing for coin-actuated machines, as herein shown and described.

FRANK T. PARRITT.
